UNITED STATES PATENT OFFICE.

HERBERT D. BADER AND JAMES CLARENCE WASELL, OF ST. LOUIS, MISSOURI, ASSIGNS TO SIMMONS HARDWARE COMPANY, OF ST. LOUIS, MISSOURI, A CORPORATION OF MISSOURI.

PACK-SADDLE.

1,239,755.

Specification of Letters Patent. Patented Sept. 11, 1917.

Application filed February 14, 1917. Serial No. 143,610.

To all whom it may concern:

Be it known that we, HERBERT D. BADER and JAMES CLARENCE WASELL, citizens of the United States, residing at the city of St. Louis and State of Missouri, have invented certain new and useful Improvements in Pack-Saddles, of which the following is a specification.

Our invention relates to pack saddles, and more particularly to a device of that character adapted to be mounted upon pack-animals, for the transportation of ammunition for machine guns.

The object of the invention is the provision of a saddle which combines the minimum of weight with the maximum of strength, rigidity and consequent durability.

A further object of the invention is the provision of a device of this nature embodying carriers so constructed as to practically eliminate the possibility of any undesired movement of the articles carried thereby.

A preferred embodiment of our invention is illustrated in the accompanying drawings, forming a part of this specification, in which—

Figure 1 is a perspective view of the saddle mounted upon a pack animal,

Fig. 2 is a perspective view of the saddle, taken from the rear,

Fig. 3 is a side elevation of the front of the saddle,

Fig. 4 is a top plan view of a portion of Fig. 3,

Fig. 5 is a perspective view of one of the corners of the frame, and

Fig. 6 is a sectional perspective on line 6—6 of Fig. 4.

Referring specifically to the drawings, in which similar reference numerals indicate like parts throughout the several views, it will be noted that the framework of the saddle comprises a top, normally horizontally disposed carrier A, from which depend two downwardly inclined carriers B and C.

It will be noted that, as clearly shown in Fig. 2, the upper carrier is formed of two integral sections of angle material, comprising side walls 1 and 2, end walls 3, 4, 5 and 6 and floor members 7 and 8. In the construction of the end walls 3, 4, 5 and 6, a substantially square section of the floor members 7 and 8 is cut away, and the ends

of the walls 1 and 2 turned at an angle to the body portion, so as to contact the floor members 7 and 8.

The carrier C, see Fig. 2, comprises a frame consisting of side walls 9 and 10 and an end wall 11. Connected to the walls 9, 10 and 11, and preferably at right angles thereto, is a floor member 12, 13 and 14.

The carrier B is constructed as an exact duplicate of the carrier C, and hence a detailed description thereof is unnecessary.

The carriers B and C are rigidly secured to the carrier A, preferably by rivets passing through supporting angle bars 15, 15. These bars are riveted to the floor members 7 and 8, forming thereby the complete carrier A.

As clearly shown in Fig. 2, braces 16, 16 are secured to the walls 9 and 10 and the floor members 12 and 14, of the carrier C, said braces extending upwardly and at a greater angle than the inclined carriers B and C, and being riveted to the angle bars 15, 15, and thence downwardly and connected to the carrier B in a manner similar to its connection to carrier C. The braces 16, 16 are formed of a single piece of angle material, having the flanges 17 and 18. Near the point of engagement with the walls 9 and 10 of the carrier B or C, the braces 16 are split longitudinally and bent at an angle to form the tongues 19 and 20, through which pass rivets 21^a, effectually securing said tongues to the walls 9 and 10 and to the floor members 12 and 14 respectively.

As will be noted by an examination of the drawings, each brace 16 is notched near its center, and the legs thereof bent downwardly for engagement with the respective carriers. The braces are riveted or otherwise rigidly secured to the bars 15, 15, at a point between the points of attachment of the members 9 and 10. By this construction the angle between the braces and the bar 15 is more acute than the angle between said bar and the members 9 and 10; and therefore, as will be readily understood, a more pronounced bracing action results.

It will be observed that the construction of the braces 16, and the manner of their attachment to the carriers B and C, and to the angle bar 15, effectually prevents relative movement of the carriers B and C,

since it is practically impossible, without breakage, for the rivets to allow any pivotal movements of the members fastened thereby.

Rigidly secured at either end of the angle 5 bar 15, by bolts, rivets, or otherwise, are outwardly-extending, upwardly-curved hook members 21, provided with a flat, inclined lower face 22, for a purpose to be herein-after explained. These hooks are clearly 10 shown in Figs. 3 and 5.

To each of the braces 16, 16 is attached a block D of wood, or other relatively light, rigid material, and secured to each block is a pad or mattress E, extending below 15 the carriers B and C, for the purpose of preventing injury to the pack animal.

The harness equipment, for use in connection with our invention, includes a strap F, secured to each of the pads E, and provided 20 with rings or hooks at either end, for attachment to the breast-strap G, and to the breeching H. To the front of the frame is fastened, preferably by rivets, to the angle bar 15, a D-ring 23, for engagement with the 25 neck strap I or the bridle ring, and to the rear bar 15 is riveted a D-ring 24, for connection with the hold-back J. To the rear bar 15 is riveted a curved iron rod 25. To the opposite bar 15 are riveted two down- 30 wardly-turned hook members 26, 26. A strap K is provided with a hook or buckle, not shown, at its rear end, for engagement with the rod 25. The front end of said strap is provided with two extensions K' and K² 35 preferably terminating in rings adapted for engagement with the hooks 26, 26.

To the bottom walls of each of the carriers B and C is riveted, or otherwise secured, a curved rod or bar 27. Detachably 40 connected to said bar, by buckles or snaps, is a strap L provided with two extensions L' and L², each extension terminating in a hook or ring adapted to pass over and engage one of the hooks 21. If desirable, the bar 27 may 45 extend from the carrier at such an angle that, when the saddle rests upon the ground, the said bar will not touch the ground at its outer face. This will prevent injury to the strap L.

50 Secured to the lower inner faces of the floor members 13, of the carriers B and C, are D-rings 28, 28, to which are buckled the girth straps M, M of the saddle.

As at present constructed the boxes for 55 containing machine gun ammunition are flat and somewhat elongated, as shown in Fig. 1. The carriers A, B and C are each so proportioned, in the particular embodiment shown, as to be adapted to receive and retain four of these boxes, the manner of attachment being clearly illustrated in said figure. It will be noted that, in the position shown, any lateral or outward movement of the boxes in the carriers B and C will be resisted by the strap L, and any longitudinal 60

movement by the inclosing side walls 9 and 10. The carriers are so proportioned furthermore, that, when four boxes are contained therein, the top face of the uppermost box contacts the inclined lower face 22 70 of the outwardly extending hook members 21, which face is made, for that purpose, to lie in a plane parallel with the plane of the lower wall 11 of the carrier. This construction effectually prevents any vertical movement of the boxes, which vertical movement is also of course resisted by the extensions L' and L² of the strap L. 75

Forward or backward movement relative to the saddle, of the boxes in the carrier A, 80 is prevented by the strap K and its extensions K' and K², and by the inturned ends 3, 4 5 and 6 of the walls 1 and 2, and, obviously, the strap L prevents any vertical movement of said boxes. 85

When the boxes are to be taken from the carriers of course the snaps or rings carried by the strap extensions may be detached from their engaged hooks, or any of the buckles of the straps may be released. Manifestly, the straps G, H, I and J are provided 90 with buckles, or may be similarly provided with snap hooks for the purpose of quick engagement and disengagement with the proper elements of the saddle or pads E, E. 95

In devices of this nature, subjected as they are to rough usage, it is essential that the frame work of the saddle be of maximum strength and rigidity, consistent with the load which the pack animal is able to carry. 100 To this end, and for the sake of durability, we construct our device of iron or steel angle bars so proportioned that the framework is of great strength and of relatively light weight. We appreciate the fact, however, 105 that, where the device is not intended for such heavy usage, the framework, including the braces, might be constructed of a different and lighter material, such as wood, or a metal lighter than iron or steel, without departing from the spirit and scope of our invention. In order to impart increased rigidity, and at the same time dispense with the necessity of the use of heavy rivets, bolts, or the like, we construct the carriers B and 110 C of a single piece of angle iron suitably notched, and thereafter welded, as at 13^a, to form the substantially U-shaped carrier provided with the side, end and floor walls 9, 10, 11, 12, 13 and 14. 115

The construction and location of the braces 16 is a material feature of our invention. It will be noted that these braces are connected to the wooden blocks D, which in turn rest upon and are secured to the pads E. The said blocks D extend longitudinally of the back of the pack animal, and the weight of the load is transmitted to the animal through the braces 16 and thence through the blocks D. Manifestly the 120 125 130

weight would naturally tend to impart a fan-like spread to the carriers B and C, but this tendency is effectually prevented by the braces, each of which is rigidly secured at 5 either end to a wall and floor member of a carrier, and, at the top, to the angle bar 15, as already described and clearly shown in Fig. 3. Moreover, at the end of a day's march, or any other time when it is de- 10 sirable to rest the animal, the saddle is removed and allowed to rest on the ground. In this case the saddle would be supported by the lower corners of the inclined carriers, and the weight of the load would tend to 15 spread the members. This tendency however is resisted by the braces, as hereinbefore explained.

It is of course understood that the carriers 20 may be so proportioned as to accommodate any number of boxes, or other receptacles, of whatever shape or size.

For the purpose of drainage, the end walls 11 of the carriers B and C may be provided with apertures 11^a, 11^a.

25 While we have shown and described a preferred form of our invention, it is to be understood that we desire to secure by Letters Patent all such modifications and embodiments thereof as fall fairly within the 30 scope of the appended claims.

Having thus described our invention, what we claim and desire to secure my Letters Patent is:

1. A device of the character described 35 comprising a horizontally disposed package carrier provided with flanges arranged to afford a supporting surface for the package, and with additional flanges extending upwardly from said surface to provide side and 40 end walls for the carrier, and a depending package carrier connected at each side of and rigidly supported by said horizontal carrier, substantially as described.

2. A device of the character described 45 comprising a horizontally disposed package carrier and a depending package carrier suspended at each side of the horizontal carrier, all of said carriers being provided with flanges arranged to provide a supporting 50 surface for the package, and with additional flanges extending upwardly at an angle to said supporting surface and constituting side and end walls for the carrier, substantially as described.

55 3. A device of the character described comprising a horizontally disposed package carrier and a depending package carrier suspended from each side of the horizontal carrier, all of said carriers being provided with 60 side and end walls having inwardly extending flanges arranged to provide a supporting surface for the package, and bracing members connected to said horizontal carrier and to said depending carriers, substan- 65 tially as described.

4. A device of the character described comprising an upper package carrier, inclined package carriers suspended from each side thereof, and a brace engaging certain of the sides of the inclined carriers, and being 70 connected to the upper carrier at a point between the points of suspension of the said inclined carriers, substantially as described.

5. A device of the character described comprising an upper, rectangularly shaped 75 package carrier, two inclined rectangularly shaped package carriers connected thereto, the said carriers being provided with angularly related side and floor members, and a brace connected to certain of the side and 80 floor members of the inclined carriers and to said upper carrier, substantially as described.

6. A device of the character described comprising a horizontal frame work provided upon each side with an inclined package carrier having flanges constituting a supporting surface for the package, and a lower end wall extending at an angle to said horizontal framework, and projections on 85 said frame work extending outwardly therefrom and upwardly inclined with respect thereto, the projections being so arranged as to lie in a plane parallel to the plane of said end walls, for coöperation therewith to 90 prevent vertical movement of the package, substantially as described.

7. A device of the character described comprising an upper package carrier, and an inclined package carrier supported on each 100 side of said upper carrier, each of said inclined carriers being constructed of an integral member having flanges arranged to provide a supporting surface for the package, and other flanges extending upwardly from 105 the said surface to provide side and end walls for said carrier, substantially as described.

8. A device of the character described comprising an upper package carrier, and an 110 inclined package carrier supported on each side of said upper carrier, each of said inclined carriers being constructed of an integral member having flanges providing side and end walls for said carrier, and an integral bracing member connected to each of the said inclined carriers and to said upper carrier, substantially as described.

9. A device of the character described comprising an upper rectangular package 120 carrier, an inclined rectangular package carrier attached to each side thereof, and a bracing member attached to and connecting the said inclined carriers, said bracing member being also connected to said upper carrier at a point between the points of attachment of said inclined carriers, substantially as described.

10. A device of the character described comprising an upper package carrier of rec- 125 130

tangular formation, an inclined package carrier of rectangular formation suspended from each side of said upper carrier, bracing members extending between said inclined carriers and connected to said upper carrier, said carriers being provided with angularly related flanges constituting the side and end walls thereof, and a projection on the upper carrier disposed in a plane parallel to the plane of the end walls of the inclined carriers and adapted for coöperation therewith to pre-

vent vertical movement of the package, substantially as described and for the purpose set forth.

In testimony whereof we affix our signatures in the presence of two witnesses.

HERBERT D. BADER.
J. CLARENCE WASSELL.
